METHOD OF APPLYING ELECTRICAL CONNECTORS

James C. Macy, Westfield, N. J., assignor to Aircraft Marine Products, Inc., Harrisburg, Pa., a corporation of New Jersey

Application June 16, 1951, Serial No. 231,983

2 Claims. (Cl. 1—68)

This invention relates to a method of applying electrical connectors or terminals to wires, more particularly, connectors initially in the form of continuous strips of connector blanks, by severing the latter one by one from such strips, and pressure-crimping them onto a conductor. Such a method can conveniently be practiced, at least in part, in connection with the operation of suitable automatic or semi-automatic connector applying machines which repeatedly index a strip of connectors into position, sever the end connector blank from its strip, and pressure-crimp the end connector blank onto a wire or other electrically conductive element. This application is a continuation-in-part of my copending application Serial No. 679,630, filed June 27, 1946, now U. S. Patent No. 2,557,126, issued June 19, 1951, to which reference is made for further disclosure of a particular connector and its use.

The patent to Vernon E. Carlson, No. 2,396,913, issued March 16, 1946, discloses and claims a connector-applying machine of the type referred to above. Also many different types of similar power driven machines have been made and brought into commercial use under this patent, to apply a wide variety of electrical connectors. Such connectors include so-called "end connectors," "butt connectors" and "parallel connectors" in which a plurality of conductors extend into and are crimped in a ferrule portion of the connector, and also those terminals such as are used to permanently engage a wire or other conducting element by means of a ferrule portion and to provide a second connecting means such as a ring tongue, spade tongue, pin-contact, spring clip, etc. adapted to be fastened to binding posts, screws, receptacles, etc.

Although this invention can be practiced in connection with strips of connector of the closed ferrule type, as shown in said Patent No. 2,396,913, as well as with those having open ferrules, the type here shown for purposes of illustration, is that wherein the ferrule portion is of channel shape.

Prior to the present invention joining pieces or "knock-out slugs," segments of the metal strip stock, were usually left as spacers between successive connector-portions in the strip, e. g., as is shown in said Carlson patent. This structure had the advantage that a punch or shear blade driven with the crimping die would punch out the slug while the strip and the end connector which was to be severed therefrom remains on a straight line. Thus both the crimping of this connector to a wire and its severance from the strip were accomplished in one position by a single stroke of the machine. This construction and use of strip connectors is successful in many applications, but the metal of the "knock out slugs" is a waste and these slugs, after being punched from the strip in the connector-applying machine, become a nuisance and possibly a source of trouble by jamming in the machine.

In order to eliminate production of a scrap material at the site of the crimping operation, the connector

2

blanks are integrally connected edge-to-edge in the strip; and the present invention makes it feasible to sever connectors from such strip and sever them individually by the same operation of the machine as that which crimps the connector on the wire. This has proven invaluable in many uses of strips of connectors.

Problems presented by the need to utilize such strips were numerous, but among the more significant problems were the severance of the connector at the end 10 of the strip, the locating and retaining of said connector in the proper position to receive a wire and to be crimped thereon, and the need for a simple method of severing said connector from the strip without interfering with such retaining of the connector in such position.

This invention has as its objects the solution of these broad problems; and, as will be seen, does present a most advantageous solution which permits the use of simplified apparatus for the severing and crimping operations.

Briefly, the invention contemplates feeding the strip toward severing and crimping dies to bring the lead connector thereof into position between the crimping dies, one of which is located at a level off-set from that of the cutting edge of one of the severing dies, shearing the contact portion of one connector from the ferrule portion of the next and displacing the severed end connector from the line of its initial advance into position between the crimping dies. In this operation the crimping dies engage the ferrule portion of the connector and crimp the same while one of the severing dies severs and then moves the contact portion toward said displaced or off-set position. This obviates the need for additional knockout tabs or more complicated blanks.

Other objects will in part be pointed out and will in part become apparent from the following specification and claims taken in conjunction with the accompanying drawings. Utilization of my invention in production machines has shown the great advantages which can accrue from the use of my method. The disclosures of various embodiments should be taken, not as exhaustive, but as indicative of possibilities for modification and as suggestive of how one may adapt the invention in various other embodiments and most advantageously use my method in solving specific problems as they arise.

In the drawings:

Figure 1 is a top plan view (enlarged) of a connected strip of terminal blanks;

Figure 2 is a side view of a fragment of a strip of connectors formed from such blank with partially pre-formed ferrule;

Figure 3 is an end view of the connector with partially pre-formed ferrule;

Figure 4 is a perspective view of the terminal after its connection to an insulated conductor has been completed;

Figure 5 is a perspective view of a set of dies for applying such a terminal to a conductor;

Figure 6 is a left-side longitudinal sectional view of these dies taken at the line 6—6 in Figure 5 with illustrative connector severing means associated therewith;

Figure 7 is a view similar to Figure 6 with the wire inserted into the end connector, the dies brought together and the end connector blank sheared off and carried to the level of the lower die by the shearing operation;

Figure 1 shows a series of connected terminal blanks 20 attached head to tail in the flat form in which they leave blanking dies used in forming them. The blank 20 as shown comprises a connecting or contact portion 24 and a ferrule base portion 26 from one side of which extend ears 28 and 30 slightly tapering and longer than they are wide. A single similar ear 34 extends from the other side of the blank leaving ferrule edges 36 and 38 on opposite sides thereof. The flat terminal blank 20 is deformed to give its ferrule portion 26 a U-shaped

cross section, as shown in Figures 2 and 3, so that ears 28, 30 and 34 extend upwardly as viewed in Figures 2 and 3. Thus, the ferrules may be applied directly on bare wire or over the insulation of an unstripped wire, Figure 4, provided with insulation 42 and a multi-strand core 44.

The U-shaped ferrule portion 26, Figures 2 and 3, forms a receptacle for a wire such as is generally indicated at 40 in Figure 4. With wire 40 in position to be engaged by the ears 28, 30 and 34 of ferrule portion 26 (as shown in Figures 2 and 3), the assembly is ready to be operated upon by the installation or crimping dies 46 and 48 (see Fig. 5). Such dies may conveniently be mounted in a press or any other suitable mechanism capable of forcing the dies together with sufficient pressure to attach the terminal to the wire. The upper die 46 in the arrangement shown in Figs. 5, 6 and 7 may conveniently be made of three die plates 50, 52 and 54, each of which is channeled in such a manner as to provide a rounded die face 80, 62 or 60. These die faces are adapted to curl the ears 28, 30 and 34 to a radius smaller than that of the exterior of the wire 40 and at the same time to force them into the wire, as are ears 28 and 34 in Figure 4, in such a manner that the ends of the ears intimately engage the wire (piercing the insulation thereon in the case of the insulated wire), or around the wire, as ear 30 in Figure 4; and are held with the remainder of the ferrule, tightly pressed against the wire. This process is more fully disclosed and claimed in my above-mentioned copending application Serial No. 717,842; the dies themselves are also more fully disclosed and claimed in my copending application Serial No. 10,021, filed February 21, 1948.

Referring to Figures 6 and 7, the composite thickness of die plates 50, 52 and 54 is substantially equal to the length of die surface 84 in lower die 48; an extension 88 in the lower die acts as a nest to support wire 40 (Fig. 7) in front of die plate 54.

In Figures 6 and 7, representative means are shown for severing the end connector 20e from the strip which has been fed or advanced to bring the lead connector thereof to a position between the dies at a level offset, in this case slightly above, the anvil surface 84 of the lower crimping die 48. A shear blade or die 45 associated with the upper crimping die 46 is disposed so as to present a shear edge 43 directly above or opposite the junction between the end connector 20e and the next to the end connector which rests on a support member 47 presenting a cutting or shear edge 49 in operating relationship to that of the shear blade. As the upper crimping die 46 and shear blade 45 move downward the ferrule portion 26, ears 28, 30 and 34 of the end connector are engaged by the die set 46, 48; and the shear blade 45 shears contact or tongue 24 of the end connector 20e from the ferrule portion 26 of the next connector in the strip and displaces said end connector from its initial unsevered position toward the level of the lower crimping die 48 while the upper crimping die 46 is moving toward said lower crimping die 48.

Generally, my method, as seen from Figures 6 and 7, permits the end connector 20e to be properly located for crimping, sheared from the strip and then retained by the lower crimping die as the upper crimping die 46 is driven to the bottom of its stroke. Obviously the crimping dies may be reversed as to position, i. e., the upper die may be the anvil, the lower die having the ear-curling surfaces.

I claim:

1. The method of making an electrical connection which includes providing a continuous strip of electrical connectors respectively having ferrule portions with outside surfaces and inside surfaces adapted to embrace and be crimped onto conducting elements, said ferrule portions alternating with contact portions in the strip, the ferrule portion of each connector being attached directly to the contact portion of the next connector adjacent to the centerline of the strip, feeding said strip toward the region between opposed dies of a crimping die set so as to bring a ferrule portion of a connector at the end of said strip between said dies while the outside surface of the ferrule portion of the next connector in the area immediately adjacent the junction with the contact portion of the end connector is supported on an anvil at one side of said dies at a level offset above that of the corresponding die face of the crimping die set, inserting a conducting element between said crimping dies in position to be embraced by said ferrule portion of the end connector, pressing both the ferrule portion and the contact portion of the end connector below said anvil in a direction away from the inside surface of the ferrule portion of the next connector thereby severing the end connector from said strip and smoothing the severed edge of the inside surface of the ferrule portion of the next connector for embracing another conducting element without cutting said other conducting element, and crimping said ferrule portion of the end connector onto said conducting element by bringing together said crimping dies.

2. The method of making an electrical connection wherein a connector having a ferrule portion and a contact portion is attached to an electrical conductor, which includes the steps of providing a strip of said connectors arranged with the contact portion of each directly contiguous in said strip with the ferrule portion of an adjacent connector, advancing said strip intermittently to bring the leading connector into position with its ferrule portion between and spaced from co-operating crimping dies and with its contact portion in the path of movement of a shearing die while rigidly supporting the outside of the ferrule portion of the connector next behind the lead connector at a position opposite the approach side of the shear edge of said shearing die, shearing said contact portion of the lead connector from the ferrule portion of said next-to-the-lead connector and applying pressure to displace said lead connector to a position aligned in said crimping dies and offset from its unsevered position and crimping said ferrule portion of the end connector onto a conductor by moving together said crimping dies.
